Primary Examiner — Derrick E Holland*Assistant Examiner* — Jennifer O King(74) *Attorney, Agent, or Firm* — Daryl R. Wright; Greg Carr(57) **CLAIM**

We claim the ornamental design for a battery hold-down apparatus, as shown and described.

DESCRIPTION

FIG. 1 is a top, left, front perspective view of a battery hold-down apparatus;

FIG. 2 is a top plan view thereof;

FIG. 3 is a right side elevation view thereof;

FIG. 4 is a front elevation view thereof;

FIG. 5 is a rear elevation view thereof; and,

FIG. 6 is a top, left, front perspective view of a battery hold-down apparatus, shown in use.

The broken lines shown in FIGS. 1–6 represent portions of the battery hold-down apparatus that form no part of the claimed design. The additional broken lines shown in FIG. 6 depict environment and also form no part of the claimed design.
